UNITED STATES PATENT OFFICE.

PAUL TSCHANNEN, OF OERLIKON, NEAR ZURICH, SWITZERLAND.

HAT-HOLDER.

1,290,810.

Specification of Letters Patent.

Patented Jan. 7, 1919.

Application filed June 27, 1916. Serial No. 106,165.

To all whom it may concern:

Be it known that I, PAUL TSCHANNEN, a citizen of the Confederation of Switzerland, and residing at Oerlikon, near Zurich, Switzerland, have invented certain new and useful Improvements in Hat-Holders, of which the following is a specification.

The present invention has reference to certain new and useful improvements in hat holding devices, and its particular object is to provide hat holding means, which will readily accommodate variously sized hats, of stiff or soft material, and which will securely, yet without any undue strain on the fabric, support the hat in an upright or inverted position, if desired in conjunction with a special hat box or trunk. With these and other objects in view, my invention resides essentially in the construction, arrangement and coöperation of parts, as will now be fully described with reference to the accompanying drawings, in which—

Figure 1 shows a side elevation, partly in section, of a preferred form of construction; Fig. 2 a bottom view thereof; Fig. 3 a section on line A—A of Fig. 1; Figs. 4—7 show details parts, partly sectioned, of a modification; Figs. 8 and 9 show respectively a side elevation and a cross-section of still another modification; Fig. 10 represents a plan view of Fig. 8, slightly altered; and Fig. 11 shows a modified construction of spring braces.

In the hat holder construction according to Figs. 1—3 the base board 1 is provided with a handle 2, and to its underside are pivoted at 3 two angular, two-part spring braces 4, 4', preferably bent of a single length of wire, with a loop 5 at the elbow joints. To the free ends of the shanks 4, is pivoted a curved presser plate 6, preferably lined with a soft material, such as for instance plush. Intermediate the links or hinges 3 are provided on the board two angular curved presser cheeks 7, 7', which on their operative faces are also plush lined, and whose upper, outer edges extend to above the lower face of the base board, as clearly shown in Fig. 3.

To each of the plate members or cheeks 7' is secured a sleeve 8, loosely embracing the board, and secured on a metal strip 9. These

latter are partly superposed and are each provided with a longitudinal slot 10 (Fig. 2), through which coinciding slots extends 55 a clamping screw 11, secured in the board 1. On loosening the nut 12 on the screw 11, the two strips 9 can be relatively displaced, with corresponding displacement of the cheeks 7' away or toward one another. Tightening 60 of the nut 12 then secures the parts in the adjusted position. A linked eye 13 serves to suspend the device in horizontal position. To the tail end of the board is pivotally secured in a support 14 an eye 15 for suspending 65 the device vertically. Near the handle end 2 is secured to the upper face of the board 1 a support 16, of the same height as the support 14, so that the device can rest on these two supports, after the two eyes 13 70 and 15 have been laid over parallel with the board. In each wire loop 5 of the spring braces is retained a ring 17, and in one of these is secured one end of a resilient, adjustable ribbon 18 (in Fig. 2 shown partially 75 broken away), whose other end carries a hook member 18' adapted to be hooked into the other ring 17.

The hat, which in the several figures is shown in broken lines, is placed in the holder 80 device as follows: The holder is placed on a table or the like support in such manner that the spring members 4, 4' extend upwardly. The ribbon 18 is unhooked, the spring braces are swung outwardly about 85 their links 3 (as shown in the left half of Fig. 1), the nut is unscrewed, and the hat is placed on top of the board 1. The brace plates or cheeks 7, 7' are moved up against the inner circumferential edge of the hat, 90 without however exerting any pressure thereon, and they are then locked by tightening of the nut 12, which presses the sliding strips 9 against the board 1. Next, the pivoted cheeks 6 are brought into contact 95 with the outer circumference of the hat, clamping the hat in coöperation with the respectively oppositely disposed cheeks 7, without any undue strain being put upon the hat. The hooked ribbon 18 then is made to 100 connect the two spring portions 4', 4', which secures the several parts in their respective operative positions.

The device can now be laid on a closet

shelf, with the hat in upright position, or it can be hung up vertically by its eye 15, which would be especially desirable in case a wet hat is to be dried.

- 5 The device may be so constructed, that it can readily be placed in a container, such as a hat box or trunk. For this purpose the base board lacks the handle 2, and at either end a special fitting 50, as shown in Fig. 4, 10 is provided. Each of these end fittings is provided with two eyes, one for receiving the cross-member connecting the ends of the spring member shanks 4, and the other for receiving the suspension ring 15, and at 15 the upper part the fitting is angularly bent to present a tongue 19. At two diametrically opposed points the hat box or trunk 20 is provided with a pocket-shaped bracket 21, having a cut-out 22 in front (Fig. 7), 20 and a spring member 23 in the front part of which a slot 24 is provided. On insertion of the hat holder into the container 20 the spring members 23 are pushed back either by hand or by the tongues 19, until 25 the latter engage in the cutouts 22, when the spring members 23 snap forward, with the tongues 19 entering their slots 24. The hat holder is now securely locked in position within the container.
- 30 The presser cheeks may also be made interchangeable, in which instance the cheek portions 7 are separate from the portions 7'. To the latter, then, is secured a rectangular extension 25, which is bent back 35 upon itself to form an elastic tongue 26, provided with a slot 27 (Figs. 4 and 5). To each cheek part 7 is secured a sleeve 28, which is provided with an inturned tooth 29, and the sleeve 20 surrounds the part 25 40 and the tongue 26, so that the tooth 29 engages in the slot 27 of the tongue part 26, whereby the relative position of the several parts is assured. The ends of the spring shanks 4' are retained in pockets of a cross-piece 30, which latter is provided in all with 45 four such pockets, as shown in Fig. 6, in the two outer ones of which the respective ends of a yoke 31 are retained. The latter carries the presser cheek 6. This interchangeability of the presser cheeks 6 may, 50 obviously, also be effected in any other suitable manner, and allows of the use of differently curved presser cheeks to accommodate various hat sizes.
- 55 The modification illustrated in Figs. 8 and 9 is especially adapted for use on soft felt hats. In the main this construction is essentially identical to the above described construction, and like reference letters denote like parts. To the base board 1 are 60 removably secured two wire yoke members 32, which serve to support the holder on a suitable base. Above the board 1 a wire ring 33 is removably secured to the supports 14 and 16 for the purpose of safe-

guarding the hat against touch. In place of the wire ring, a solid disk 34 (shown in broken outline in Fig. 10), suitably supported on the base board, may be used to advantage.

70

Fig. 11 shows a special construction of spring members, which operate without the use of the tension ribbon 18. These spring members have a hollow elbow member 35, pivoted to the base board and pressed by the bow spring 39 against the presser cheeks 7, the springs being secured at the lower ends to the board. The presser cheeks 6 are preferably yieldingly connected to the elbow members in telescopic manner, as 80 shown in the drawing.

75

For putting in or taking out a hat, the elbow members are swung outwardly, as shown in dotted outline in the righthand part of Fig. 11, and are locked in the open 85 position by the perforated ends of the springs 39 snapping over studs or hooks 40 extending from the elbows.

85

What I claim is:—

1. In a hat holder in combination, a base 90 board, angular presser members thereon, their upstanding cheeks adapted to engage the interior, and its base portions adapted to support the brim of the hat at opposite points, angular spring brace members pivoted near the extremities of said base board, presser cheeks on the free end of said spring members, adapted to engage the outside of the hat in coöperation with said internal presser members, and means for retaining 95 the coöperating sets of presser members 100 in coöperative position.

95

2. In a hat holder, in combination, a base board, angular presser members thereon, their upstanding cheeks and their base portions being suitably padded and adapted to engage respectively the interior and the lower face of the hat brim, means for relatively displacing said presser members to accommodate hats of different sizes and for locking them in the desired operative position, resilient presser members on said base board, adapted to clampingly coöperate with the said angular presser members, means for securing said resilient presser members in the operative position pressed against the exterior of the hat, and means for suspending said base board in different positions.

105

3. In a hat holder, in combination, a base 120 board, inner angular presser cheeks, means for adjustably retaining said cheeks on said board, comprising two superimposed members adapted to slide one upon the other and having coinciding longitudinal slots, a sleeve 125 secured to each of said sliding members and sliding on said board, and a clamping means fixed to said board and extending through said slots, adapted to lock said sliding members relative to one another and the said 130

110

115

120

125

130

board, resilient pressure braces pivoted to said board, presser cheeks at the free ends of said braces, means for retaining said braces with their cheeks in operative position, comprising bow springs secured with one end to said board and bearing with the other end against said braces, means for locking said braces in the inoperative posi-

tion, and means for suitably suspending the said board.

In testimony whereof I affix my signature in presence of two witnesses.

PAUL TSCHANNEN.
